UNITED STATES PATENT OFFICE.

JEPHTHA G. HOLLINGSWORTH, OF KANSAS CITY, MISSOURI.

DENTAL APPLIANCE.

1,101,439.

Specification of Letters Patent. Patented June 23, 1914.

Application filed August 29, 1913. Serial No. 787,356.

To all whom it may concern:

Be it known that I, JEPHTHA G. HOLLINGSWORTH, a citizen of the United States, residing at Kansas City, in the county of 5 Jackson and State of Missouri, have invented certain new and useful Improvements in Dental Appliances, of which the following is a specification.

This invention relates to a dental appliance for use in the preparation of fillings, such as described in my application for patent for method of preparing dental fillings, filed February 21, 1914, and my object is to provide a device by means of 10 which gold leaf and enamel fillings may be prepared by cold process entirely outside the mouth of the patient, ready to be inserted in the tooth cavity and secured in place by cement, thereby eliminating the 15 pain and discomfort incident to the usual filling operations when performed in the mouth.

To this end my invention comprises a holder for receiving a matrix which has been 20 prepared from an impression of the tooth cavity, and means for clamping the filling material about the matrix while being molded therein, provision being made for all requisite adjustments between the holder 25 and clamping means. In the case of amalgam or other plastic fillings, the clamping means includes a strip or band of pliable transparent material for engaging the filling material as well as holding it under pressure and receiving the contact of the tools 30 whereby the filling material is worked into the matrix, so that any possibility of the filling being marred or tarnished by chemical action sometimes resulting from contact 35 of the filling material with metallic substances is avoided, and the transparency of the clamping band enables the operator to observe and follow closely the outlines of the work.

Having these objects in view, the invention resides in certain peculiar and novel features of construction as hereinafter described and particularly pointed out in the appended claims; and to afford a full and 40 clear understanding thereof, reference will be had to the accompanying drawings, forming a part of this specification, and in which—

Figure 1 is a side elevation, partly in 45 vertical section, of the device as arranged for cold gold fillings; Fig. 2, is a front

elevation of the same; Fig. 3, is a section along the line III—III of Fig. 1, looking in the direction of the arrow; Fig. 4, is a front elevation of the device as arranged 60 for plastic or amalgam fillings; Fig. 5, is a side view of the device provided with a slightly modified form of clamping attachment; Fig. 6, is a bottom plan view of 65 said clamping attachment the clamping band being omitted; Figs. 7 and 8 are side and plan views respectively, showing another form of clamping attachment.

Referring to the drawings, the base portion 2 of the device is provided with a central socket 4 into which is threaded the shank portion 6 of a matrix holding plug 8, provided with a top recess 12. The recess is slightly undercut, as shown in Fig. 1, and provided with a bottom channel 14, 70 in order to receive and lock within the top of said plug a bed 16 of sealing wax on which to mount the cement matrix 18.

Adapted to embrace the shank portion 6 of the plug 8, is a clamping yoke 20, having 75 resilient arms normally in loose sliding engagement with the shank 6. Through the extremities of said yoke arms extends a bolt 22, said bolt sliding freely through one of 80 said extremities and threaded to engage the other extremity and thereby draw said yoke arms together into clamping engagement with said shank portion 6. The arrangement is such that the yoke is adjustable in 85 any horizontal direction upon the shank of 90 said plug. The yoke carries at one end an angular arm 24, the upper end of which extends parallel with the yoke so as to overlie the wax bed 16 and matrix carried thereby. This upper end of said arm has threaded therethrough a clamping post 26, which 95 may be adjusted into clamping engagement with the parts carried by the bed 16, as shown in Figs. 1 and 2. This use of the post is preferred in the preparation of cold 100 gold fillings, in which process a wax impression is taken of the tooth cavity and embedded in quick setting cement to form the matrix 18. This matrix is then applied to the bed of hot wax 16, said bed being 105 built up around the sides of the matrix and the wax impression withdrawn before it is melted by the heat from the bed 16. The bed 16 is then mounted in the top of the plug 8, and the pliant character of this bed, 110 while it remains soft under the influence of heat, permits the cement matrix 18 to be

positioned at any desired angle with reference to the bed to facilitate the carrying out of the filling operation. When the bed has cooled and hardened, so as to retain the matrix securely in position and form a firm support therefor the yoke 20 and post 26 are adjusted to bring the latter into clamping relation with the leaf or mat gold with which the cavity in the matrix is to be filled, the gold being condensed either by hand, or mallet or engine burnisher, as preferred. The lower end of the post 26 may be readily set at any point on the bed 16, and the angular supporting arm 24 permits easy access to the work and observation thereof from any angle.

In the case of plastic or amalgam fillings it is desirable to clamp the filling material in the matrix tightly while it is being molded to the contour of the matrix, and at the same time avoid any contact of the tools with the filling. I accomplish this by clamping the filling material by means of a band or strip 28 of pliable transparent material, such as celluloid, the central portion of which is disposed over the filling material and the ends of the band secured preferably to a yoke 30 by means of buttons 32 formed on the extremities of the yoke and engaging eyes 34 of the band. The lower end of the post 26 is diametrically reduced at 36 to form a downwardly disposed shoulder 38 to bear upon the upper side of the central portion of the yoke 30, the reduced extremity 36 of the post extending through the yoke to hold the same in fixed relation to said shoulder 38. By this means, upon the adjustment of the post the yoke will be brought down to tighten the band about the filling material, the outline of which will at all times—owing to the transparency of the band—be clearly discernible to the operator, who will thus be enabled to quickly work the filling to the proper contour and without any contact of his instruments therewith.

A modification of the clamping attachment for plastic fillings is shown in Figs. 5 and 6, in which case the clamping band is made sufficiently long to secure it to buttons 40 provided on the base portion 2 of the device, and the intermediate portions of the band are drawn inward by resilient arms 42 carried by a pin 44 on one end of a bar 46. This bar is provided with an opening 48 for receiving the shank of the matrix holding plug 8, whereby the bar may be clamped to the base 2 as shown in Fig. 5. When so applied, the resilient arms 42, by pressing in on the depending portions of the band 28, cause the latter to be drawn tightly against the filling and matrix, and the parts are held in this relation by the hooked ends 50 of said arms being locked together as shown.

In Figs. 7 and 8, I show the clamping band provided with enlargements 52 for

retaining the ends thereof within open ended slots 54 in the ends of a yoke 56 which yoke is carried by a stem 58 having a recess 60 for embracing the arm 24. A clamping screw 62 is provided for clamping said stem to said arm. The recess 60 is enlarged toward its bottom so that on tightening up the screw 62, the yoke 56 will be given a downward movement acting to clamp the band 28 snugly over the bed 16 and the parts carried thereby.

From the foregoing it will be apparent that I have devised a very simple, compact and efficient means for carrying out the objects of my invention, and while I have illustrated and described what now appears to me to be the preferred forms of the same, I desire to reserve the right to any modifications thereof which may fall within the spirit and scope of the appended claims.

I claim:

1. In an apparatus of the character described, a matrix holder, a device for clamping the material to be molded to said matrix, and means for supporting said device adjustably adjacent to the matrix.

2. In an apparatus of the character described, a matrix holder provided with a cementitious bed for receiving the matrix, a device for clamping the material to be molded to said matrix, and means carried by said holder for supporting said device adjacent to the matrix.

3. In an apparatus of the character described, a matrix holder having a reduced stem portion, a device for clamping the material to be molded to said matrix, said device being provided with a clamping yoke for securing the device to said stem portion.

4. In a dental appliance, a matrix holder comprising a base portion and a top portion detachably secured to said base portion, said top portion being provided with a recess for receiving a cementitious bed for the matrix.

5. In a dental appliance, a matrix holder comprising a base portion having a socket, a top portion having a stem for detachably engaging said socket, and a clamping member for clamping the material to be molded to said top portion, said member being provided with a resilient clamping yoke for securing said member to said stem.

6. In a dental appliance, a matrix holder comprising a base provided with a bed upon which to support the matrix, a yoke extending to the sides of said bed, and carrying means for clamping the material to be molded to said matrix, and means for adjustably securing said yoke to said base.

7. In a dental appliance, a matrix holder comprising a base, provided with a bed upon which to support the matrix, a pliable clamping band adapted to overlie said bed, and means for clamping said band tightly around said bed.

8. In a dental appliance, a matrix holder comprising a base provided with a bed upon which to support the matrix, a pliable transparent clamping band adapted to overlie said bed, a yoke detachably engaging said band at its opposite ends, and means for adjusting said yoke and causing it to clamp said band tightly about said bed.

9. In a dental appliance, a matrix holder, comprising a base provided with a bed upon

which to support the matrix, a pliable transparent clamping band adapted to overlie said bed, and means for clamping said band tightly about said bed.

In testimony whereof, I affix my signature, 15 in the presence of two witnesses.

JEPTHA G. HOLLINGSWORTH.
